UNITED STATES PATENT OFFICE

170,903

MEDICINAL VAPORIZER

Aaron Barkin, New York, N. Y., assignor to Practical Electric Products, Inc., Bronx, N. Y., a corporation of New York

Application January 5, 1953, Serial No. 22,999

Term of patent 7 years

(Cl. D83—1)

To all whom it may concern:

Be it known, that I, Aaron Barkin, a citizen of the United States, residing at New York city, State of New York, have invented a new, original, and ornamental Design for a Medicinal Vaporizer, of which the following is a specification, reference being had to the accompanying drawing, forming a part hereof.

Fig. 1 is a view in elevation of a medicinal vaporizer, embodying my new design,

Fig. 2 is a top plan view, and

Fig. 3 is a perspective view thereof.

I claim:

The ornamental design for a medicinal vaporizer, as shown.

AARON BARKIN.
